DESIGN FOR A SLIDE FASTENER PULL

Noel J. Poux, Meadville, Pa., assignor to Talon, Inc., Meadville, Pa., a corporation of Pennsylvania

Application July 7, 1939, Serial No. 85,874

Term of patent 14 years

To all whom it may concern:

Be it known that I, Noel J. Poux, a citizen of the United States, residing at Meadville, in the county of Crawford and State of Pennsylvania, have invented a new, original and ornamental Design for Slide Fastener Pulls, of which the following is a specification, reference being had to the accompanying drawing, forming a part thereof.

In the drawing:

Fig. 1 is a front elevational view of a slide fastener pull, showing my new design;

Fig. 2 is a side view of the pull;

Fig. 3 is a view of the pull shown in Fig. 1 as seen from the end thereof, as indicated by the lines 3—3; and

Figs. 4 and 5 are perspective views of the pull.

I claim:

The ornamental design for a slide fastener pull, substantially as shown.

NOEL J. POUX.
